I. B. GILBERT

DEVICE FOR AUTOMATICALLY GRINDING VALVES FOR COMBUSTION ENGINES

Filed April 9, 1921

Inventor
Israel B. Gilbert
By Walter F. Murray
Attorney

UNITED STATES PATENT OFFICE.

ISRAEL B. GILBERT, OF CINCINNATI, OHIO, ASSIGNOR OF ONE-HALF TO ORLIN J. CUTLER, OF CINCINNATI, OHIO.

DEVICE FOR AUTOMATICALLY GRINDING VALVES FOR COMBUSTION ENGINES.

Application filed April 9, 1921. Serial No. 460,020.

To all whom it may concern:

Be it known that I, ISRAEL B. GILBERT, a citizen of the United States of America, and a resident of Cincinnati, in the county 5 of Hamilton and State of Ohio, have invented a new and useful Improvement in a Device for Automatically Grinding Valves for Combustion Engines, of which the following is a specification.

10 An object of my invention is to provide means whereby the valves of engines may be automatically ground and cleaned during the operation of the engine.

Another object of my invention is to provide 15 means for the purpose stated, which may be readily placed in and out of operative condition.

Another object is to provide means for the 20 purposes stated that are simple in construction and operation and subject to a minimum of wear.

These and other objects are attained by the means described herein and disclosed in the accompanying drawings, in which:—

25 Fig. 1 is a fragmental elevation of a combustion engine having a device embodying my invention mounted thereon and operative upon the valve.

Fig. 2 is an enlarged sectional view on 30 line 2—2 of Fig. 1.

Fig. 3 is a sectional view on line 3—3 of Fig. 2.

Fig. 4 is an enlarged sectional view on line 4—4 of Fig. 1.

35 Fig. 5 is a view similar to Fig. 2, showing a modified form of my invention.

My invention comprises a series of studs *a* mounted on a cam shaft *A* of a combustion 40 engine, each of which is adapted to oscillate the stem of one of the valves *B*. The oscillating motion of the valve serves to grind the valve face *b'* upon the valve seat *b''*.

The cam shaft *A* is of the type and kind 45 ordinarily used in combustion engines, having mounted upon it the cams *a'* adapted to actuate the inlet and exhaust valves such as *B*. The studs *a* are mounted upon the cam shaft adjacent the cams *a'*. It is preferable to form threaded ways *a²* in the cam shaft 50 in which the studs *a* are adapted to be adjustably seated. Suitable means such as the lock nuts *a³* are provided to secure the studs in their adjusted positions.

A valve plunger *C* is adapted to engage the cams *a'*, as is common in the art, and to be longitudinally reciprocated by means of the cams *a'* and the spring *S*, adapted to yieldingly retain the valve plunger upon the cam. The valve tappet screw *c* is adjustably mounted upon the valve plunger and is 55 adapted to be secured thereupon in its adjusted position by means of a lock nut *c'*, as is common in the art. The slots *c²* are formed in the top of the valve plunger adapted to accommodate lugs *d* formed on 60 the link *D* mounted upon the valve stem *b*.

The link *D* may be made in any shape and form provided it does not interfere with the relation of the valve tappet screw *c* and the valve stem *b*. The link serves merely to 70 transmit rotatory or oscillatory motion from the valve plunger *C* to the valve stem *b*. I have shown the link as comprising a top plate *d'* having a bore *d²* adapted to accommodate the valve stem *b* secured thereto by 75 the pin *d³*, and a bottom plate *d⁴* having a central bore *d⁵* adapted to accommodate the upper end of the valve plunger and in which the upper end of the valve plunger can be freely reciprocated longitudinally. The 80 branches *d⁶* connect the top and bottom plates.

The valve stem *b*, upon the upper end of which is mounted the valve *B*, is adapted to engage at its lower end upon the valve tappet adjusting screw *c*, as is common in the art. A washer *b'* is mounted upon the stem *b* and forms an abutment for one end of the spring *S*, the other end of which spring engages part of the combustion chamber housing *E*. 85

The lower end of the valve plunger *C* has a bore *c⁴* within which is mounted a rod *F*. Normally the rod extends parallel with the cam shaft *A* and is yieldingly retained in 90 this position by means of a spring *G* secured upon the free end of the rod *F* and upon the housing *E*. The rod *F* is spaced at such distance from the cam shaft *A* that the studs *a* on the cam shaft may be adjusted so as to engage the rod as the studs revolve about the axis of the cam shaft. An arm *H* is mounted upon the valve plunger and extends therefrom at an angle to the rod *F*. A cable *J* is attached at one of its ends 100 upon the free end of the arm *H*, and has its 105

other end secured upon a lever J^2 mounted at any suitable place accessible to the operator, whereby it is possible to retain the valve plunger and rod F in such positions that the studs a will not engage the rods.

In Fig. 5 there is shown a modified form of device embodying my invention. In this modified form a secondary rod F' is mounted upon the valve plunger C and extends from the plunger at an angle to the primary rod F at a place substantially opposite to the rod F . A secondary stud A' is mounted upon the cam shaft A and is adapted to engage the secondary rod F' after the primary stud a has become disengaged from the primary rod F . In this modified form the spring G is dispensed with, so that the primary stud a and the secondary stud A' alternately actuate the valve plunger in opposite directions. The arm H and the cable attached thereto may be employed with either construction.

The operation of my device is as follows:

The cam shaft A is revolvably actuated by the engine, whereby the cams serve to longitudinally reciprocate the valve B , thereby alternately seating and unseating the valve. During certain portions of the cycle of the cams the valves engage their seats, and during this portion of the cycle, the studs a engage the rods F and revolvably actuate the valve plungers as the studs move by the rods F . After the disengagement of the studs from the rods, the springs G return the rods to their normal positions. This oscillatory motion of the valve plunger is transmitted through the link D to the valve stem and valve, whereby the valve is oscillated upon its seat and thereby grinds and cleans both itself and its seat.

In the modified form the spring G is dispensed with, wherefore the engagement of the primary stud with the primary rod F serves to move the secondary rod F' to a position parallel with the cam shaft A and in which the secondary rod will be engaged by the secondary stud. The secondary stud in turn operates the valve plunger so as to return the primary rod to its normal position in parallelism with the cam shaft A , in which position the primary rod will be again engaged by the primary stud.

The cleaning mechanism is rendered inoperative by retaining the rods in such position that they will not be engaged by the studs, this being accomplished by means of the cable J and the lever J^2 .

What I claim is:

1. The combination with a combustion engine of means adapted to oscillate the valves upon their seats during the operation of the engine, whereby the valves and valve seats are cleaned.

2. The combination with a combustion engine having means to alternately seat and

unseat the valves controlling the intake and exhaust of the combustion chamber, of means actuated by said first mentioned means to oscillate the valves upon their seats, whereby the valves and valve seats clean and grind one another. 70

3. The combination with a combustion engine having valve seats and valves adapted to be actuated longitudinally by means of cams, of studs mounted adjacent the cams adapted to oscillate the valves upon the seats. 75

4. The combination with a combustion engine having a cam shaft, and valves adapted to be reciprocated in relation to the cam shaft, of a valve plunger engaging the cam shaft adapted to actuate the valve, a link adapted to transmit rotary motion from the valve plunger to the valve, and means actuated by the cam shaft adapted to oscillate the valve plunger in opposite directions in alternate sequence when the valve is on its seat. 80

5. The combination with a combustion engine having a cam shaft, and valves adapted to be reciprocated in relation to the cam shaft, of a valve plunger engaging the cam shaft adapted to actuate the valve, a link adapted to transmit rotary motion from the valve plunger to the valve, means actuated by the cam shaft adapted to oscillate the valve plunger in opposite directions in alternate sequence, and means to render the last mentioned means inoperative. 85 90

6. The combination with a combustion engine having a cam shaft and valves adapted to be reciprocated in relation to the cam shaft, of a valve plunger adapted to be reciprocated in alignment with the valve engaging the cam shaft, a link mounted upon the valve stem adapted to transmit rotary motion from the valve plunger to the valve stem, a rod mounted on the valve plunger adapted normally to assume a position adjacent the cam shaft and in substantial parallelism with the axis of the cam shaft, means yieldingly retaining the rod in its normal position, and an adjustable stud mounted upon the cam shaft adapted to engage the rod and to move the rod from its normal position. 100 105 110

7. The combination with a combustion engine having a cam shaft and valves adapted to be reciprocated in relation to the cam shaft, of a valve plunger adapted to be reciprocated in alignment with the valve engaging the cam shaft, a link mounted upon the valve stem adapted to transmit rotary motion from the valve plunger to the valve stem, a rod mounted on the valve plunger adapted normally to assume a position adjacent the cam shaft and in substantial parallelism with the axis of the cam shaft, means yieldingly retaining the rod in its normal position, an adjustable stud mounted upon the cam shaft adapted to engage the 115 120 125 130

rod and to move the rod from its normal position, and means to retain the rod in an inoperative position.

8. The combination with a combustion engine having a cam shaft and valves adapted to be reciprocated in relation to the cam shaft, of a revoluble valve plunger engaging the cam shaft and adapted to actuate the valve, a link mounted upon the valve stem and adapted to transmit rotary motion from the valve plunger to the valve stem, and means mounted upon the valve plunger and the cam shaft adapted to oscillate the valve plunger in opposite directions in alternate sequence.

9. The combination with a combustion engine having a cam shaft and valves adapted to be reciprocated in relation to the cam shaft, of a revoluble valve plunger engaging the cam shaft and adapted to actuate the valve, a link mounted upon the valve stem and adapted to transmit rotary motion from the valve plunger to the valve stem, means mounted upon the valve plunger and the cam shaft adapted to oscillate the valve plunger in opposite directions in alternate sequence, and means adapted to render the last mentioned means inoperative.

10. The combination with a combustion engine of means adapted to oscillate the valves upon their seats during the operation of the engine, whereby the valves and valve seats are cleaned, and means to render the first mentioned means inoperative.

11. The combination with a combustion engine having valves adapted to be actuated longitudinally by means of cams, of studs

mounted adjacent the cams adapted to oscillate the valves, and means yieldingly resisting oscillation of the valves.

12. The combination with a combustion engine having valves adapted to be actuated longitudinally by means of cams, of studs mounted adjacent the cams, and means operative on the valves adapted to engage the studs and be oscillated thereby.

13. The combination with a valve and seat therefor, of means for yieldingly retaining the valve upon its seat, means to oscillate the valve upon its seat, and means to render the oscillating means inoperative upon the valve.

14. The combination of a poppet valve and means for oscillating said valve when it is seated.

15. A valve, means for reciprocating said valve, and means for oscillating said valve when it is seated.

16. A valve, means for reciprocating said valve, means for oscillating said valve, and means for rendering said oscillating means ineffective.

17. A poppet valve and valve stem, and means for engaging said stem and rotating it first in one direction and then in the opposite direction, when the valve is seated.

18. A poppet valve and valve stem, a cam, and means carried by the valve stem and engaging the cam whereby the valve is rotated, when it is seated.

In testimony whereof, I have hereunto subscribed my name this 6th day of April, 1921.

ISRAEL B. GILBERT.
